UNITED STATES PATENT OFFICE

SHERMAN Q. FRENCH, OF HAWARDEN, IOWA.

WINDOW LOCK.

Application filed June 27, 1924. Serial No. 722,755.

To all whom it may concern:

Be it known that I, SHERMAN Q. FRENCH, a citizen of the United States, residing at Hawarden, in the county of Sioux and State of Iowa, have invented certain new and useful Improvements in a Window Lock, of which the following is a specification.

This invention relates to new and useful improvements in window locks and has reference more particularly to a device which is adapted to be associated with a sliding window for holding the same in any desired adjusted position with respect to the window frame, thereby obviating the necessity of employing the usual weights and sash cords.

Another important object of the invention is to provide a window lock of the above mentioned character, which may be readily and easily actuated for locking or unlocking the window as is desired.

A further object of the invention is to provide a window lock of the above mentioned character, which is simple in construction, inexpensive, strong and durable and furthermore adapted for the purposes for which it is designated.

Other objects and advantages of this invention will become apparent during the course of the following description.

In the accompanying drawing forming a part of this specification and in which like numerals designate like parts throughout the same:

Figure 1 is a fragmentary side elevation of a window with the lower portion thereof shown in section and illustrating the manner in which my improved window lock is associated therewith, the same being in locked position.

Figure 2 is a sectional view taken approximately on line 2—2 of Figure 1.

Figure 3 is a fragmentary edge elevational view of the window showing the pocket arranged therein, and

Figure 4 is a detail perspective view of one of the blocks.

In the drawing wherein for the purpose of illustration is shown the preferred embodiment of my invention, the numeral 1 designates a window which is of the sliding type and as the same may be of any conventional construction, a further detailed description thereof is not thought necessary. The window frame in which the window is adapted for slidable movement is designated at 2 in the drawing. Provided in the bottom

sill 3 of the window sash 1 and arranged centrally therein is the enlarged opening or recess 4. Secured to the outer face of the bottom sill 3 of the window and adapted to cover the recess 4 is the plate 5. The fastening means for the plate is illustrated at 6 with reference more particularly to Figure 2.

Extending centrally through the opening or recess 3 and also through a similar opening in the plate 5 is the substantially square-shaped shaft 7. The inner end of the shaft is journaled in a suitable pocket 8 provided in the sill 3 and on the outer end of the shaft which extends laterally from the bottom sill of the window a suitable knob or handle 9 is secured. Carried by the intermediate portion of the shaft 7 are the eccentrics 10 and 11 respectively. The eccentrics are spaced from each other as well as being spaced from the sides of the enlarged recess 4 through the medium of the washers 12. The eccentrics are further of such diameter as to permit the same to freely operate in the enlarged annular recess 3 in the manner hereinafter to be more fully described.

Extending around the eccentrics 10 and 11 respectively are the enlarged inner ends of the rods 13 and 14 respectively. The inner ends of the rods are of such construction as to fit around the periphery of the eccentrics and the outer ends of the rods are each provided with the reduced portion 15. The rods extend from the eccentrics in opposite direction into the transversely extending openings 16 and 17 respectively, the same extending from the enlarged annular recess 4 to the opposite side edges of the window 1 and communicate with the cut out portions or pockets 18 arranged in the side edges of the window sash.

Extending longitudinally in the transversely extending recesses are the tubular members 19 and 20 respectively and the inner ends thereof are adapted to receive the reduced portion of the rods 13 and 14 in the manner more clearly illustrated in Figure 1. The outer ends of the tubular members carry thereon the heads 21 which are adapted to operate in the pockets 18 in the manner also hereinafter to be more fully described.

Seated in the pockets 18 provided in the side edges of the window sash 1 and adapted for engagement with the jamb of the window frame 2 are the blocks 22. The blocks are preferably formed of wood and for the purpose of preventing the head 21 on the

outer ends of the tubular members from defining the blocks, the inner faces of the blocks are provided with the metallic plates such as is shown at 23 whereby heads 21 will 5 engage the metallic plates when moving the blocks into engagement with the jambs of the window frame.

When the parts are arranged as shown in Figure 1 of the drawing, the blocks 22 are 10 moved outwardly from the pockets and into engagement with the jambs of the window frame whereby the window sash is held in any desired adjusted position. When it becomes necessary to raise or lower the window, as the case may necessitate, the knob or handle 9 is rotated so as to cause the eccentrics 11 and 12 to retract the tubular members through the medium of the rods 13 and 14 whereby the blocks 22 will not bind 15 20 against the jambs of the window frame and permit the free sliding movement of the window sash.

The provision of a window lock of the character above described will obviate the 25 necessity of having to employ the usual weights and sash cords and the pulleys asso-

ciated therewith. The simplicity of my device enables the same to be readily installed on windows of the sliding types now in use and will further be inexpensive, yet strong 30 and durable and positive in its operation.

While I have shown the preferred embodiment of my invention, it is to be understood that various changes in the size, shape and arrangement of parts may be resorted to 35 without departing from the spirit of the invention and the scope of the appended claim.

Having thus described the invention, what I claim is:—

In a window retaining device of the kind 40 specified, an oscillatory shaft provided with a handle, eccentrics carried by said shaft, mounting means for said shaft, a pair of rods extending in opposite directions and provided at their inner ends with concentric 45 ring-like head surrounding said eccentrics, a tube into which each rod telescopes, a head on the outer end of each tube, and a metal faced block forming a brake shoe, said head bearing against the facing.

In testimony whereof I affix my signature.

S. Q. FRENCH.
